UNITED STATES PATENT OFFICE.

JESSE P. SHORT, OF GREENSBURG, INDIANA.

VALVE GRINDER.

Application filed April 30, 1923. Serial No. 635,493.

My invention relates to improvements in valve grinding tools and it is one of the objects of my invention to provide a valve grinding tool for grinding the valves of 5 automobile engines and the like, which tool may be easily clamped in position on the motor block of that type of engine which is provided with a removable cylinder head.

Another object of my invention is to provide 10 means for positioning the valve oscillating member with respect to the valve and maintaining it in its position so that the valve will be truly centered. Other objects and advantages of my invention will appear 15 more fully in the accompanying specification and claims.

For the purpose of disclosing my invention I have illustrated certain embodiments thereof in the accompanying drawings in 20 which—

Fig. 1 is a perspective view of my grinding tool mounted in position on the cylinder block;

Fig. 2 is a longitudinal sectional view of 25 my tool;

Fig. 3 is a sectional view taken on the line 3—3 of Fig. 2;

Fig. 4 is a perspective view of a modified 30 form of the valve engaging wrench; and

Fig. 5 is an elevation partly in section of a slightly modified form of my grinding 35 tool.

In the embodiment of my invention illustrated, I provide a tubular standard 1 which 40 is adapted to be secured on the top of the motor block by a clamping screw 2. This screw is threaded at its lower end to engage in the bolt holes which are ordinarily provided for holding the cylinder head in position 45 on the cylinder block and extends through the standard 1, being provided at its upper end with a hand wheel 3 by which the screw 2 is screwed into the screw hole and between which and the top of the cylinder block the standard 1 is rigidly clamped.

The valve grinding mechanism proper is positioned by this standard 1 and this grinding mechanism comprises a central spindle, or stem, 4 having at its lower end a pin-projection 5 adapted to engage in the centered recess, or socket, of the valve. The spindle, or stem 4 is slidably mounted in a bearing formed at the outer end of an arm 6 extending laterally from the standard 1. This arm, in order to permit of an adjustment of the spindle 4 laterally relatively to the

standard 1, is preferably formed of two sections, one section 7 being telescoped between a pair of arm sections 8 extending from the standard 1 and slotted to permit the passage therethrough of a clamping bolt 9. The valve oscillating tool comprises a tubular stem 10 having a foot member 11 provided with spaced-apart prongs 12 adapted to engage in the slot formed in the top of the valve or in the grinding tool openings formed in the top of the valve. These prongs are spaced apart and are arranged on either side of the projection 5. The stem is also provided with an oscillating handle 13 and is rotatably mounted upon the spindle 4. It is urged into engagement with the valve by means of a pressure member 14 likewise slidably mounted on the spindle 4 and between the lower end of which and the stem 10 is arranged a coil spring 15 so that as the operator forces the pressure member 14 down the spring 15 will be placed under compression thereby urging the valve oscillating member into 80 engagement with the valve. This member 14 is provided with a transversely extending slot 16 to accommodate the arm 6 and permit the member 14 to vertically move on said arm.

In order that valves having various types of grinding tool recesses may be operated upon, I may if desired, provide the form of an oscillating tool illustrated in Fig. 4. In this type of tool the head 11^a is removable 90 mounted on the tool and may have various types of valve engaging projections 12^a. The tool proper at its lower end is provided with a pair of projections 17 adapted to seat in sockets 18 on the upper 95 face of the head to prevent relative rotation between the stem 10 and the head. The head is held in position by a pair of spring fingers 19 arranged to clamp on either side of the head and provided with inturned 100 lugs 20 arranged to engage beneath the head.

Those tools which are adapted for one specified type of engine need not be provided with the adjustable arm 6 as illustrated in Fig. 2, but as illustrated in Fig. 5 105 this arm may be of a standard length and in one piece as shown in Fig. 5.

In operation the standard 1 is clamped on the engine block by means of the screw 2 which engages in the threaded bolt opening of the cylinder head. In most engines these bolt openings are spaced equidistant

between two valve openings so that after one valve has been ground the apparatus may be swung to grind a second valve without removing the tool. The standard having 5 been securely clamped in position on the engine head, the operator, by compressing the spring 15, may raise the head 11 sufficiently beyond the projection 5 so that this 10 projection will be clearly visible and then lower the spindle 4 until this projection 5 is seated in the center socket of the valve. By exerting pressure upon the upper end of the pressure member 14 the spring is 15 sufficiently compressed to force the head 11 closely into engagement with the valve, with the projections 12 engaging in the tool receiving openings of the valve. The operator may then oscillate the stem 10 on the spindle 4 by means of the handle 13 20 to properly seat and grind the valve in position.

I claim as my invention:

1. In a valve grinder, the combination 25 with a standard arranged to be rigidly mounted on an engine block, of a spindle arranged to engage the valve and be main-

tained by said standard in axial alignment with the stem thereof, a valve oscillating member journaled on said spindle, a pressure member vertically movable on said spindle and a spring interposed between said pressure member and said oscillating member to maintain the oscillating member in engagement with the valve.

2. In a valve grinder, the combination 35 with a standard arranged to be rigidly mounted on an engine block and having an offset bearing in alignment with the valve stem guide, a spindle vertically movable in said bearing and maintained in axial alignment with the valve stem, an operating member oscillating the valve, rotatably mounted on said spindle and vertically movable thereon, a pressure member vertically movable on said spindle and a coil spring 40 interposed between said pressure member and said valve oscillating member.

In witness whereof, I, JESSE P. SHORT, have hereunto set my hand at Greensburg, Indiana, this 25th day of April, A. D. one 50 thousand nine hundred and twenty-three.

JESSE P. SHORT.
